UNITED STATES PATENT OFFICE.

LOREN L. WHITNEY, OF HAMMOND, INDIANA, ASSIGNOR TO AMERICAN STEEL
FOUNDRIES, OF NEW YORK, N. Y., A CORPORATION OF NEW JERSEY.

METHOD OF FORGING FULCRUMS.

1,323,341.

Specification of Letters Patent.

Patented Dec. 2, 1919.

Application filed January 15, 1917. Serial No. 142,428.

To all whom it may concern:

Be it known that I, LOREN L. WHITNEY, a citizen of the United States, and resident of Hammond, in the county of Lake and State of Indiana, have invented certain new and useful Improvements in Methods of Forging Fulcrums, of which the following is a specification.

My invention relates to railway brake beams and has particular reference to a novel method of forging fulcrums for use therein.

In Patent No. 1,157,833 to Carl E. Bauer, dated October 26, 1915, a method of forging fulcrums was disclosed, by means of which method a fulcrum of desirable form was produced. It has been found, however, that in some instances a fulcrum is desired having an eye at its end instead of a saddle for the accommodation of the tension rod. An object in the present invention is to provide a novel method of forging whereby this eye may be formed simultaneously, or substantially so, with the formation of the fulcrum.

The method will be disclosed in connection with the illustrations in the accompanying drawings, in which—

Figure 1 is a view of the fulcrum showing its condition after the first forging operation;

Fig. 2 is a similar view showing its condition after the second forging operation;

Fig. 3 is another view of the construction shown in Fig. 2, and

Fig. 4 is a view of the completed fulcrum, the eye having been completed by drilling or punching.

The first steps in the forging operations may be similar to those disclosed in the

Bauer patent heretofore referred to. By those steps a member is formed having parallel twisted side members 10, 11, a thick end wall 12 and lateral terminal portions 13, 14, for engagement with the compression member of the beam. The next operation is to clamp the member of Fig. 1 in suitable dies and to bulldoze the end to form the web or thin lug 15, the plane of which is at right angles to the plane of the lateral extensions

13, 14. In effect the same action occurs in the formation of this web 15 as in the formation of the saddle shown in the patent heretofore referred to. It is, however, necessary to cause a more pronounced lateral

deflection of the metal in the production of 55 the eye.

The next operation is that of drilling or punching out the hole 16 through which the tension rod extends. In the forging operation it will be noted that the bearing or seat 60 17, indicated in dotted lines in Fig. 2, is formed simultaneously with the web 15, the flanges 18 being provided above and below the seat in order to securely retain the tension rod. 65

Obviously the steps in the method may be varied to a certain extent without materially altering the final result and therefore the appended claims should not be construed to be limited to the exact order stated therein. 70

I claim:

1. The method of forging brake beam fulcrums, which consists in bending a flat bar to provide parallel twisted side members and a thickened end wall, then upsetting 75 said end wall to form a thin lug at right angles to the tension rod seat and located in a vertical position with relation to the beam when in service, then providing a transverse perforation in said web for the accommodation of a tension rod, substantially as described. 80

2. The method of forging brake beam fulcrums, which consists in doubling a bar of metal upon itself and providing a thickened end wall, then bulldozing said end to provide a tension rod bearing and an endwise projecting web which extends across said bearing and at right angles thereto, then perforating said web at the point of said bearing to provide an eye for the accommodation of a tension rod, substantially as described. 85

3. The method of forging brake beam fulcrums, which consists in doubling a bar of 95 metal upon itself, then bulldozing the closed end of the so-formed member to provide a tension rod seat which is bisected by a solid transverse web, then perforating metal of the web at the seat whereby an eye is 100 formed, substantially as described.

Signed at Chicago, Illinois, this 11th day of January, 1917.

LOREN L. WHITNEY.
